(No Model.)

L. HAAS.

UNDERGROUND TELEGRAPH.

No. 268,661.

Patented Dec. 5, 1882.

UNITED STATES PATENT OFFICE.

LEVI HAAS, OF CHESTER, PENNSYLVANIA.

UNDERGROUND TELEGRAPH.

SPECIFICATION forming part of Letters Patent No. 268,661, dated December 5, 1882.

Application filed July 3, 1882. (No model.)

To all whom it may concern:

Be it known that I, LEVI HAAS, a citizen of the United States of America, residing at Chester, in the county of Delaware and State of Pennsylvania, have invented certain new and useful Improvements in Underground Telegraphs, of which the following is a specification, reference being had to the accompanying drawings.

10 This invention relates to improvements in underground telegraphing; and it consists in the employment of sections of pipe with longitudinal openings or slots therein, and fitted with plugs or lids; secondly, in means for stretching or tightening the wires.

15 In the accompanying drawings, Figure 1 shows a sectional view of sections of pipe arranged at a point where the wires branch off in different directions embodying my invention. Fig. 2 is a view of the curved portion of the pipe. Fig. 3 is a view of the pipe disconnected, showing the wires in position. Fig. 4 is a plan view of the disk B.

20 In carrying out my invention, I employ sections of pipe A A, having longitudinal openings or slots a in them to permit the ready insertion of the wires which said pipe-sections are designed to hold. After the wires are inserted and the filling poured in plugs or lids 25 are placed over the openings or slots to prevent the ingress of moisture or earth, and to retain the filling-matter in place. These pipe-sections are filled with an insulating material composed of the ingredients hereinafter described, in connection with the insulator disks or plugs for the wires. B B' are glass plugs or disks for supporting the wires of the lines 30 intact with the pipe-sections. These plugs or disks are provided with angular slots or slits

35 b to receive and permit the wires to be held by the disks or plugs, and are formed larger or smaller in diameter, as required, to fill their place in the pipe—*i. e.*, the large disk fits over the small end of the pipe, while the smaller disk fits inside the same. Through disk B, to 40 and through disk B', extends a screw-bolt, C, with nuts or burrs to draw the disk B' toward the disk B for the purpose of tightening the wires. These disks or plugs are made of glass,

and are molded or cast; or they may be made 50 of terra-cotta clay burned and well glazed, glass, however, being preferable. Said disks are inserted through the slot in the pipe, then turned to a position crosswise of the pipe, each disk presenting an angular slot or slit in line 55 with the slot in the pipe, through which a single wire is pressed into the angular slot or slit in the disks. The disks are then rotated until the next slot or slit is presented, when another wire is inserted in the same way, and 60 so on until the whole number of wires are inserted in place. Then the ground insulating material is poured in, filling the pipe. Cement of the usual kind, crushed or ground soapstone, or clean and sharp white sand, or 65 ground stone-delf, or the glassy slag of blast-furnaces may be used for the insulating material to fill in the pipe-sections. Said material is ground fine and poured into the pipe through the longitudinal slot. A complete insulator 70 is thus provided throughout the line or lines. The insulator-disks B' are arranged suitable distances or intervals apart and from the end plugs, B. Those adjacent to the end disks or plugs, B, have the wires looped or knotted 75 at the points where said wires pass through them, and are adjusted with relation to the plugs B by screw-bolts C, having nuts and washers to effect the stretching or tightening of the wires. The plugs B are placed against the 80 shoulder on the inside of the enlarged end of the pipe A, and the small end of the opposite section of pipe A is forced against the plug B, thereby holding the same in place. This arrangement permits the turning of the plugs or 85 disks.

I claim and desire to secure by Letters Patent—

1. In combination with a conduit formed of slotted pipe-sections, each of said sections being provided with a bell-mouth at one end, of disks B', fitted to the inner circumference of the smaller end of the pipe, and the disks B, constructed, as described, to fit over the end, and bolt C connecting the said disks, as shown 90 and described.

2. In combination, the slotted pipe-sections, provided with the stationary disk B and mov-

able disk B', pierced with angular slots or slits to receive the wires, said wires being looped or knotted at their ends, which rest against the face of the disk, as described, the 5 screw-threaded bolts passing through the center of said disks, and provided with nuts to draw the disks toward each other to tighten the wires, as shown and described.

In testimony whereof I affix my signature in presence of two witnesses.

LEVI HAAS.

Witnesses:

STEPHEN E. HAAS,
PERRY M. WASHABAUGH.
